UNITED STATES PATENT OFFICE.

HARRY ADAMS, OF THE UNITED STATES NAVY.

PHONOGRAPH.

1,274,361.

Specification of Letters Patent.

Patented Aug. 6, 1918.

Application filed October 25, 1916. Serial No. 127,540.

To all whom it may concern:

Be it known that I, HARRY ADAMS, a citizen of the United States, of the United States Navy, have invented certain new and 5 useful Improvements in Phonographs, of which the following is a specification.

My invention relates to a toy phonograph or sound producing device and the object of my invention is to produce a toy phonograph which is novel in construction and 10 operation, simple to operate and portable and also light in weight so that a child can readily handle and operate the device, and a further object of my invention is to produce a toy phonograph which can be manufactured at a very small cost.

Referring to the drawings in which like reference characters refer to like parts;

Figure 1 is a side elevation of the phonograph;

Fig. 2 is a front elevation of Fig. 1;

Fig. 3 is a detached view of the spindle upon which the record cylinder is mounted;

Fig. 4 is a sectional view of the record 25 cylinder; and Fig. 5 is a sectional view showing mechanism for increasing the speed of the record cylinder.

In the accompanying drawings 1 represents the body portion or frame, which may 30 be made of stamped metal having sufficient rigidity to form a bearing for handles 2 and 3 located at either end of the frame 1. The handles 2 and 3 are located upon opposite sides of the frame 1 and are mounted at 35 right-angles with the frame. Both of the handles are free to turn in the frame. The handle 2 being loosely mounted on the rod 4 secured in the frame. The handle 3, is formed integral with a shank or spindle 6, 40 which is provided with a screw thread, forming a means for detachably securing the sound record cylinder 8 upon the spindle 6, to permit the records to be readily changed.

The sound record cylinder 8 consists of a 45 cylindrical drum open at one end to form a sound box to amplify the sound. A threaded sleeve 9 is formed centrally upon the record cylinder. Said sleeve 9 is adapted to be screwed upon the spindle 6 of the handle 3, so that the record cylinder 8 will rotate with 50 the spindle 6. Upon the outer cylindrical surface of the record cylinder 8 is impressed the record which is to be reproduced by the phonograph.

55 The record cylinder 8 may be formed of thin metal or any other suitable material

but I prefer to make it of papier mâché. The record may be impressed directly into the material forming the record cylinder or the record may be formed upon some other material placed upon the cylinder, as shown in Fig. 4.

A diaphragm 12 carrying a stylus 13 is securely held in a rigid rim 14 which is carried by an arm 15 pivotally mounted upon 65 the pivot pin 16 secured in the plate 17 which is pivoted upon a pin 18 secured in a bearing 19 formed upon the frame 1. A spring 20 is secured at one end thereof by a rivet 22 and the opposite end of the spring is attached to the arm 23 forming part of the hinged plate 17. The spring 20 tends to hold the stylus 13 against the record cylinder and the pivot pin 16 forms a hinge which permits the diaphragm to have a lateral movement which allows the stylus 13 to follow the spiral groove upon the record cylinder 8.

The diaphragm frame 14 is provided with a small finger grip 24 by which the diaphragm frame and the hinged plate 17 may 80 be swung upon the pivot pin 18 and the diaphragm moved away from the record cylinder 8, for the purpose of changing the record cylinders.

It will be seen that by holding the handle 85 3 securely in one hand and rotating the other end of the frame around the handle 3, as a center, that the diaphragm will be moved around the record cylinder and the stylus will be moved over the record groove 90 formed in the record cylinder and produce the sound.

The speed of the rotation of the record cylinder 8, in relation to the rotary movement given to the handles may be increased 95 by attaching to the handle 30 a gear wheel 31, as shown in Fig. 5. The handle 30 is loosely mounted in the frame 1, and the gear wheel 31 meshes with a gear wheel 32, of smaller diameter, secured upon the shaft 100 33 upon which the threaded spindle is mounted for receiving the record cylinder. By holding the handle 30 rigid and rotating the frame around the handle the larger gear wheel will rotate the smaller gear wheel at 105 a faster speed and cause the record cylinder to rotate more rapidly.

Having thus described my invention I claim and desire to secure by Letters Patent:—

1. In a device of the character described, the combination of a portable frame, a

sound record rotatably mounted in the frame, a diaphragm, a plate to which the diaphragm is pivotally mounted, a pivot pin upon the frame upon which the said plate is pivotally mounted, a spring engaging the plate and tending to hold the diaphragm adjacent to the record and means for operatively moving said parts in relation to each other.

19 2. In a device of the character described, the combination of a frame, a handle located at each end of the frame said handles disposed in opposite directions and at right angles with length of the frame, a sound record connected with one of said handles and a diaphragm upon the frame.

20 3. In a device of the character described, the combination of a frame, a handle located at each end of the frame, said handles rotatably mounted in the frame, a spindle integral with one of said handles, a sound record secured upon said spindle and a diaphragm upon the frame.

21 4. In a device of the character described, the combination of a frame, handles located at the ends of the frame, a sound record

secured upon one of said handles, a diaphragm pivotally mounted upon said frame at a point between the two handles and a stylus upon said diaphragm for engaging the sound record.

22 5. In a device of the character described, the combination of a frame, handles located at the ends of the frame, a sound record mounted upon one of said handles, a diaphragm mounted upon the frame, a stylus on the diaphragm held in engagement with the sound record, and the whole structure so arranged that when the handle carrying the sound record is held in one hand and the frame is revolved about the axis of the sound record the said stylus will move around the sound record and reproduce the sound waves which have been recorded upon the sound record.

23 In testimony whereof I affix my signature in the presence of two witnesses.

HARRY ADAMS.
